UNITED STATES PATENT OFFICE

DE WITT H. WYATT, OF COLUMBUS, OHIO, ASSIGNOR TO FRIGIDAIRE CORPORATION,
OF DAYTON, OHIO, A CORPORATION OF DELAWARE

DESIGN FOR A FAUCET FOR WATER COOLERS OR THE LIKE

Application filed August 30, 1929. Serial No. 32,629. Term of patent 14 years.

To all whom it may concern:

Be it known that I, DE WITT H. WYATT, a citizen of the United States, residing at Columbus, in the county of Franklin and State of Ohio, have invented a new, original, and ornamental Design for Faucets for Water Coolers or the like, of which the following is a specification, reference being had to the accompanying drawing, forming part thereof.

In the drawings:

Fig. 1 is a front elevation of the faucet, showing my new design;

Fig. 2 is a side elevation of the faucet; and
Fig. 3 is a top plan view of the faucet.

I claim:

The ornamental design for a faucet for water coolers or the like, as shown.

In testimony whereof I hereto affix my signature.

DE WITT H. WYATT.
